UNITED STATES PATENT OFFICE.

JOSEPH H. GREGORY, OF MORRIS PLAINS, NEW JERSEY.

DESIGN FOR A GUARD-RING FOR BRIDLE-BITS.

No. 38,989.

Specification for Design

Patented Jan. 7, 1908.

Application filed October 9, 1907. Serial No. 396,688. Term of patent 14 years.

To all whom it may concern:

Be it known that I, JOSEPH H. GREGORY, a citizen of the United States, residing at Morris Plains, in the county of Morris and State of New Jersey, have invented a new, original, and ornamental Design for a Guard-Ring for Bridle-Bits, of which the following is a specification, reference being had to the accompanying drawing, forming part thereof.

The figure is a side view of a guard ring for bridle bits, showing my new design.

I claim:

The ornamental design for a guard ring for bridle bits, as shown.

JOSEPH H. GREGORY.
